UNITED STATES PATENT OFFICE.

WALTER S. PIERCE, OF NEW YORK, N. Y.

CALCINING APPARATUS.

SPECIFICATION forming part of Letters Patent No. 505,956, dated October 3, 1893.

Application filed October 31, 1891. Serial No. 410,482. (No model.)

To all whom it may concern:

Be it known that I, WALTER S. PIERCE, a citizen of the United States, residing at New York city, in the county and State of New York, have invented a certain new and useful Improvement in Calcining Apparatus, of which the following is a specification.

The object of my invention is an apparatus which will effect a uniform and equable drying of any finely divided material, such as phosphates of alumina and iron.

In carrying out my invention I provide a revoluble cylinder into which the material to be calcined is introduced; the inner surface of this cylinder I provide with a series of blades running longitudinally of the cylinder, each blade being inclined from the feed end of the cylinder toward the discharge end, and said blades occupying only a portion of the inner circumference of the cylinder. I also arrange in the cylinder a series of longitudinal ribs, each separated from the other by some considerable space, a sufficient number of the ribs being employed to extend from near one end of the inclined blades around the cylinder. The purpose of the inclined blades is to both feed and tumble the material undergoing treatment. They, in conjunction with the longitudinal ribs, effect an additional tumbling whereby it is insured that the material undergoing treatment will be thoroughly and equally subjected to the calcining action. Any suitable method of heating may be used, as may any suitable devices for rotating the cylinder and feeding and discharging the material undergoing treatment, my improvement relating especially to the cylinder.

In the accompanying drawings illustrating a form of apparatus embodying my invention, Figure 1 is a side elevation, partly in section, of said apparatus; and Fig. 2 is a cross-sectional elevation taken on the plane of the broken line $x-x$ of Fig. 1.

45 A represents a furnace provided with the usual accessories of grate, ash - pan, flue, doors, &c.

B is a shaft or axle carried in suitable bearings C supported from the masonry work of

the furnace, said axle being driven by suitable gearing B' bolted to the driving power.

D is the calcining cylinder carried by the axle B, upon which it is supported by the spiders E. This cylinder is provided at its feed end with an internal flange F projecting inward at right-angles to the axle, the purpose of which is to prevent the material which is fed into the cylinder from the hopper G from falling out. A longitudinal series of blades H are fastened to the inner side of the cylinder. Each of said blades is somewhat scoop-shaped in form as shown in Fig. 2 and is inclined from the feed toward the exit end of the cylinder, the last blade H of the series extending somewhat beyond the cylinder end, as shown in Fig. 1, so as to insure a proper discharge of the material. I have shown but a single series of these blades, though a greater number may be employed without departing from my invention. For a cylinder thirty inches in diameter and twenty feet in length I prefer to employ a single row of blades H as shown, each blade being about two feet long and five inches deep with an inclination toward the axis of the cylinder of about forty-five degrees, each blade in the series being separated from its neighbor by about one foot.

In addition to the blades H I provide in the cylinder a series of longitudinal ribs I, as best shown in Fig. 2, the depth of these ribs I for a cylinder of the dimensions given above being about one and a half inches. These ribs may be arranged at uniform distances apart and any desired number may be employed.

In operation the material to be treated is fed into the cylinder to a depth somewhat less than the depth of the blades H, and upon the rotation of the cylinder these blades, by reason of their inclination, feed the material forward, effecting, in combination with the ribs I, a thorough tumbling of the material and a regular movement thereof through the cylinder, thereby insuring a uniform and rapid calcining.

I claim—

A cylinder for a calciner revolvably sup-

ported and provided on its inner periphery with a longitudinal series of blades occupying only a portion of the inner circumference of the cylinder, each blade of the series being inclined with relation to the axis of the cylinder, and a series of longitudinal ribs extending around the inner circumference of the cylinder from near one end of the series

of inclined blades to near the other end, substantially as set forth.

This specification signed and witnessed this 28th day of October, 1891.

WALTER S. PIERCE.
